CARL L. GUSTAFSON, OF CHICAGO, ILLINOIS

WORK-HOLDING CLAMP

Application filed November 30, 1928. Serial No. 322,836.

This invention relates to improvements in a carpenter's clamp or the like and has for one of its principal objects the provision of means for quickly and conveniently adjusting the jaws of the clamp for any desired span.

In the usual clamp or vise the only means for moving the jaws of the same when a different span is desired is by the use of the 10 clamp screw. Obviously this is a slow tedious process when a great variation in span is desired.

One of the important objects of this invention is to provide means in conjunction with 15 a device of the class mentioned, for disengaging the clamp screw from the threads contained in the fixed jaw, thereby permitting the screw to be slid through the fixed jaw, and in turn drawing the movable jaw toward 20 or away from the fixed jaw. When the approximate span is obtained the screw can be readily positioned operatively with respect to the fixed threads and the device may then be used in the ordinary manner.

25 Other and further important objects of the invention will be apparent from the disclosures in the accompanying drawings and following specification.

The invention, in a preferred form, is illustrated in the drawings and hereinafter more fully described.

In the drawings:

Figure 1 is a side elevation of the clamp.

Figure 2 is a detail sectional view, illustrating in particular the screw engaging and disengaging mechanism.

Figure 3 is a detail plan sectional view showing the screw operatively associated with the segmental thread.

40 Figure 4 is a detail sectional view of the screw end housing.

Figure 5 is a sectional view taken on the line 5—5 of Figure 1.

As shown in the drawings:

45 The reference numeral 10 indicates generally a screw of the usual square thread type ordinarily used for translation purposes. One end of the screw is provided with a rigidly attached handle member 12. The 50 other end of the screw is positioned loosely

in an opening 14 in a movable clamp jaw 16. As shown best in detail section in Figure 4, the end of the member 10 has mounted thereon a cap 18, the mounting comprising a rivet 20 or the like positioned transversely through the screw 10 and cap 18. A housing 22 is mounted upon the member 16 and completely encloses the end of the screw 10 and the cap 18, an oil hole 24 being provided in the same for lubricating purposes. 55

The movable jaw 16 is adapted to slide upon a leg 26 which in turn is rigidly connected to a fixed jaw 29. To facilitate the sliding of the member 16 upon the leg 26 and decrease wear at the sliding surfaces, the 60 two operative edges of the leg 26 are provided with metal facings 28 attached to the leg by means of countersunk screws or the like 30. A guide 32 also provided with a metal face 34 is rigidly attached to the jaw 65 16 and operates at the rear edge of the leg 26 thus preventing the jaw 16 from assuming other than a right-angle position on the leg 26. 70

The screw 10 is also positioned through an 75 opening 36 in the fixed jaw 28. The opening 36 is tapered inwardly and adapted to be inserted therein is a member 38 which is flanged at one end for readily mounting the same on the edge of the jaw 28. One portion 80 of the inner surface of the member 38 comprises a semi-cylindrical threaded element 40. It is apparent that by means of the taper construction of the member 38 the screw 10 can be engaged and disengaged by moving 85 the same into and out of operation with the thread segment 40. Mounted loosely upon the screw 10 is a sleeve or collar 42 having integrally attached to one end thereof a notched hand-wheel 44. Rigidly attached to 90 one face of the said hand-wheel and extending outwardly therefrom is a pin 46. As shown best in Figure 2, the sleeve 42 when placed in operative position in the opening 95 36 places the screw 10 in engagement with the threaded segment 40, thus adapting the clamp to slow motion clamping action. Obviously when the sleeve is removed from the opening the screw is freed from the threads and the screw may be slidably moved 100

as desired, thus permitting a rapid change of span of the jaws 16 and 28.

It is apparent that herein is provided a device which is convenient, extremely useful 5 and rugged and a saving of both time and labor can be effected by its use.

I am aware that many changes may be made and numerous details of construction varied throughout a wide range without departing from the principles of this invention, 10 and I therefore do not purpose limiting the patent granted hereon otherwise than as necessitated by the prior art.

I claim as my invention:

15 1. In a carpenter's clamp, a pair of jaws movable relative to each other, a screw operatively associated with each jaw and means for rendering the screw inoperative as such with respect to one of the jaws, said means including a semi-cylindrical internally threaded member, one of the jaws being provided with a tapered opening into which the said member is adapted to be housed, the screw being adapted to be inserted in the said opening and means for removably positioning the screw relative to the threaded semi-cylindrical member.

20 2. In a carpenter's clamp, a pair of jaws movable relative to each other, a screw operatively associated with each jaw and means for rendering the screw inoperative as such with respect to one of the jaws, said means including a semi-cylindrical internally threaded member, one of the jaws being provided with a tapered opening into which the said member is adapted to be housed, the screw being adapted to be inserted in the said opening and means for removably positioning the screw relative to the threaded semi-cylindrical member, said means comprising a collar slidably mounted on the screw, and adapted to be inserted in the opening in the said jaw and means on the collar for holding the screw in operative position with respect to the segmental threads.

25 3. In a carpenter's clamp, a pair of jaws movable relative to each other, a screw operatively associated with each jaw and means for rendering the screw inoperative as such with respect to one of the jaws, said means including a semi-cylindrical internally threaded member, one of the jaws being provided with a tapered opening into which the said member is adapted to be housed, the screw being adapted to be inserted in the said opening and means for removably positioning the screw relative to the threaded semi-cylindrical member, said means comprising a collar slidably mounted on the screw, and adapted to be inserted in the opening in the said jaw and means on the collar for holding the screw in operative position with respect to the segmental threads, said means including an annular member rigidly mounted on the collar, a pin rigidly mounted on the annular

member, the said pin being adapted to cooperate with the tapered side of the opening.

4. A carpenter's clamp, including in combination, a pair of jaws, one fixed and one 70 slideable, a screw passing through openings provided in each jaw, the screw being loosely positioned in the opening in the movable jaw and optionally threadedly or slideably positioned in the opening in the fixed jaw, and means upon the movable jaw for restricting 75 slideable motion in one direction of the screw relative thereto, and means upon the screw for preventing slideable motion in the other direction, of the screw relative to the jaw, said first means comprising a housing completely enclosing the end of the screw and mounted rigidly upon the jaw, the second means including a cap rigidly connected to the end of the screw adjacent the said jaw.

In testimony whereof I affix my signature. 85
CARL L. GUSTAFSON.
